UNITED STATES PATENT OFFICE

JOSEPH M. LOEFFLER, OF PHILADELPHIA, PENNSYLVANIA

DOOR OPENING APPARATUS

Application filed August 7, 1930. Serial No. 473,618.

My invention relates to devices for opening doors and it particularly has relation to such devices as are used for opening fire doors, engine house doors, and the like, and for holding the doors open.

Heretofore spring-operated articulated arms have been employed for the purpose of opening fire engine house doors (see Patent No. 998,324, to Clay, issued July 18, 1911), but in such patented structure no provisions were made for adjustment of the apparatus to open the door to more than a single angle, and further the speed at which the doors are opened by the patented structure is too slow. My invention therefore has for its objects to provide a device of the general type of the Clay device which, however, will open the doors more rapidly; to provide a device which has provisions for opening the doors to a greater or lesser angle as desired; and in general to render the operation of the device more effective and certain.

Other objects will in part be obvious and in part pointed out hereinafter.

To the attainment of the aforesaid objects and ends, my invention consists in the novel features of construction and combination, connection and arrangement of parts, hereinafter more fully described, and then pointed out in the appended claims.

In the drawings:

Figure 1 is a face view of a pair of closed doors with my invention applied.

Figure 2 is a horizontal section on the line 2—2 of Figure 1.

Figure 3 is a view similar to Figure 2 with the door open.

Figure 4 is a detail view similar to Figure 3 with the opener adjusted to open the door through a maximum angle, in full lines, and through a minimum angle, in dotted lines.

Figure 5 is an enlarged detail elevation of one of the openers.

Figure 6 is a detail plan view of the vertical supporting rod and bracket.

In the drawings, in which like numerals of reference indicate like parts in all of the figures, 1 represents the vertical supporting rod which has its angular ends 3 held in

brackets 2 that are secured to the jamb 41 of the door frame.

On the rod 1 is mounted a collar 4 secured by a set screw 5 and carrying a compound arm bracket 6 having a series of adjustment holes 7 arranged in the arc of a circle having as its center the pivotal axis of the pivot 39 when the door is in the closed position.

A bearing sleeve 8 is swivelly mounted on the rod 1 and provided with roller bearings 9 to reduce friction, a top collar 10 with set-screw 11 being mounted on the rod 1 to protect the roller bearings when such are used.

The articulated arm comprises the inner section 12 and the outer section 26 and the articulate joints 21, 23, 24, between these members 12 and 26.

The inner section 12 of the articulated arm has upper and lower studs 13 around which the ends 15 of torsion springs 14 engage. The other ends 16 of the springs 14 engage the studs 17 on the tension nuts 18 which have openings 19 in their faces to receive holding pins 20 that engage corresponding apertures in the rod 1, and thus hold the nut 18 in any position in which it may be placed to take up or let out on the spring tension.

The arm 12 at its outer end has a forked socket 21 provided with an inclined stop 22 to cooperate with the inclined face of the tongue 23 of the rod socket 25, the tongue 23 being pivoted to the socket 21 as at 24 and constitutes, as it were, a rule joint.

The rod 26 is secured to the socket by suitable set screws 27, or in any other suitable way, and has its outer end passed through an opening 29 in the door bracket 28 and engages the friction roller 30 of the bracket in the usual manner, there being a washer 31, buffer spring 32, and buffer spring tension adjusting nut 33, provided on the outer and threaded end 34 of the rod 26.

35 is what I term a compound arm having one end 36 curved and pivoted at 37 to the compound arm bracket by a connection 37 passing through one of the adjustment holes 7. The other end of the compound arm 35 is angled as at 38 and has its end pivoted at 39 to the ear 40 on the socket 25.

41 designates the door jamb, 42 the door, 43 the door hinge and 44 the axis of that hinge.

In the practical use of my invention when the members have been duly mounted, it is determined to what angle the door 42 is to be opened and the connection 37 made with the proper hole 7 so that when the door is thrown open to its maximum position it will be at the desired angle to the closed position. By changing the fulcrum 37 from one to another of the holes 7 the final angular position of the door may be correspondingly varied.

Furthermore, assuming the door to be closed, as soon as the door is released the springs 14 will begin to throw the articulated arm in a direction to move the door toward the open position. By reason of the compound arm 35 the outer end of the articulated arm moves faster than the inner section of the articulated arm, with the result that by the time the inner section 12 of the articulated arm has moved through an arc of 90° the outer section 26 will have moved through an arc of 135° (when the parts are adjusted in the position shown in Figure 2 of the drawings).

The arrangement of the holes 7 is such that an adjustment to each hole gives a variation of about 22½° movement to the outer arm section 26 and consequently of the door 42.

By adjusting the pivotal connection 37 to the innermost of the holes 7 the door is open to the least angle and by adjusting the arm 35 to the outermost of the holes 7 the door is moved to its greatest angle in approaching the open position.

On returning from the open to the closed position, the door moves faster than the inner section 12 of the arm and reaches its closed position at the same time the articulated sections of the arm come into alignment.

From the foregoing description, taken in connection with the accompanying drawings, it is thought the complete construction, operation and advantages of my invention will be readily understood by those skilled in the art.

What I claim is:

1. In door openers, a rod fixed to the door jamb, an articulated arm freely pivoted to one end of said rod, a sliding connection between said arm and the door, a compound arm pivoted at one end adjacent said rod and having its other end pivoted adjacent said arm between its articulation and its point of connection to the door, and a spring for moving said arm.

2. In door openers, a rod mounted on the door jamb, springs on said rod, an articulated arm mounted on said rod and rotatable about the axis thereof, a bracket secured to said rod, an arm having one end pivoted to said bracket and having its other end pivoted to said articulated arm beyond the articula-

tion, and a connection between said articulated arm and said door.

3. In door openers, a rod mounted on the door jamb, springs on said rod, an articulated arm mounted on said rod and rotatable about the axis thereof, a bracket secured to said rod, an arm having one end pivoted to said bracket and having its other end pivoted to said articulated arm beyond the articulation, and a connection between said articulated arm and said door, said bracket having a series of adjustment holes to receive the pivot of said second mentioned arm for the purposes described.

4. An automatic door opening device comprising a rod, means for mounting said rod on a door jamb, operating springs mounted on said rod, an articulated arm pivotally mounted on said rod and engaged by said springs, means connecting the free part of said arm to a hinged door whereby on release of the door said arm, under the influence of said spring, will move the door on its hinge through a predetermined arc, and means cooperating with the aforesaid parts for varying the angle through which said springs and arm will move said door.

5. An automatic door opening device comprising a rod, means for mounting said rod on a door jamb, operating springs mounted on said rod, an articulated arm pivotally mounted on said rod and engaged by said springs, means connecting the free part of said arm to a hinged door whereby on release of the door said arm, under the influence of said spring, will move the door on its hinge through a predetermined arc, and means cooperating with the aforesaid parts for varying the angle through which said springs and arm will move said door, said means comprising a compound arm pivoted to said free part of said first mentioned arm, and a bracket on said rod to which said compound arm is also pivoted.
